UNITED STATES PATENT OFFICE

GEORGE BAEHR, OF MCKEESPORT, PENNSYLVANIA

HOLLOW ROLL

Application filed December 14, 1926. Serial No. 154,799.

This invention relates to rolls.

More particularly it relates to composite rolls, in which a forming or face portion is separable from the driving or spindle portion.

Among the objects of the invention are to provide a roll having a separable hollow wearing face or shell that may be heated or cooled by circulating fluid therein, together with means for accurately positioning the shell portion of the roll upon the spindle portion, and of retaining it in fixed position thereon by means permitting its ready detachment.

Referring to the drawings, Fig. 1 shows an axial partial section through the roll with all of the parts in assembled position; Fig. 2 is an end view on the line II—II of Fig. 1; and Fig. 3 is a partial section on the lines III—III of Fig. 1.

As is well known in the art, rolls used for forming and finishing hot metal bars are subject to a considerable amount of wear. After the surfaces of the roll have become worn it is necessary to dismount them, resurface the worn face portion by machining, or other means. After this has been done a certain number of times, the roll is no longer useful and must be scrapped. Furthermore, the necks of the rolls sometimes break, and under present conditions that means that the entire roll is a total loss except for scrap uses of the metal as such. Also the physical characteristics suitable for the forming surface of such rolls are not those most suitable for the necks thereof.

To meet these conditions, and to provide an improved form of roll in which the wearing surface portion may be detachable from the spindle or carrying portion, a structure such as that illustrated in the drawings has been designed.

This comprises an axial spindle member 45 forging, having its end formed into wobblers 1, with adjacent necks 2, and with an intermediate body portion 3, which may be in the original forged form, without any machining. Between the middle body portion 50 3 and the necks 2, the body member is ma-

chined to form a threaded portion 4 and a smooth cylindrical portion 5, respectively, as indicated on the drawing.

The threaded portion 4 is adapted to receive an internally threaded wedge seating or support member 6; and the smooth portion 5 is adapted to receive a similar wedge member 7, which however is not threaded but merely slides thereon. These supporting wedge members 7 and 6 are preferably frusto-conical in exterior shape, with longitudinal seating ribs 14 and 14^a thereon respectively. The ribs are preferably three in number on each of members 6 and 7, giving stable support as will be obvious.

A keyway 8 is provided in the neck 2 and threaded portion 4, with a corresponding keyway in the wedge member 6, so that the latter may be held against rotation on the spindle member by insertion of a key 9, as shown at the left of Fig. 1.

A jam nut 10 is adapted to cooperate with threads on portion 5, and is a follower for the wedge member 7, for the purpose of driving and locking it in proper operative position upon the spindle.

The wearing face of the roll is formed by a hollow shell which may be made by casting, or forged, having end portions 11 and 12 with a connecting intermediate cylindrical portion 13. The ends 11 and 12 have aligned inwardly converging tapered openings adapted to seat on ribs 14 and 14^a on the outer surfaces of the wedge members 7 and 6, respectively.

The opening in the end 12 of the shell has keyways 15 adapted to receive the ribs 14, so that there can be no relative rotation between the shell and base 7. That base itself is preferably held in non-rotatable relation to the spindle by a key 9^a.

The outer face 13 of the shell member may have grooves of any desired contour machined therein for the purposes of forming bars that are to be rolled between this roll and a cooperating one of similar exterior surface, as will be understood by those familiar with the art. This member may be made of a special alloy such as adamite, or chilled iron, to give increased wearing qualities,

while the spindle may be of soft low-carbon steel for toughness and resistance to breaking strains.

5 Hardened washers may be used where necessary at the ends of the shell member, for the purpose of furnishing the contact with the housing or journal members. These will be of suitable number and thickness, and are not illustrated or claimed.

10 In making up a roll embodying this invention, the spindle member is forged in one operation. The necks and wabblers are then machined so much as is necessary, as are also the keyways, and the threaded portions 4 and 5. Holes are drilled in the outer ends of the support member 6 and in the outer face of the jam nut 10 so that they may be turned down with a spanner wrench.

15 The wedge member 6 is first turned to its proper position upon the threaded portion 4 of the roll, and the key 9 is inserted, thus locking it in position. The shell is then moved over the spindle from the opposite end of the roll, the opening in the end 11 thereof seating upon the three ribs 14^a of the support member 6. This three-point support arrangement insures that the roll will be accurately seated upon the base or wedge 6.

20 The frustro-conical wedge member 7 is then slipped on the portion 5 until the three ribs 14 upon its outer face seat in the keyways 15 of the opening in the end 12 of the hollow body member. The key 9^a is then inserted and the jam nut 10 is turned up to 25 lock the supporting member 7 in position. The cylindrical surface 13 of the roll is then machined to true it, or to form grooves therein, and the roll is ready for attachment to the usual driving mechanism. When the 30 member 13 becomes heated in use it will expand and elongate. The resulting increase of length will thrust the ends 11 and 12 against the inclined members 6 and 7. This will result automatically in a tightening of the assembly in use, rather than a loosening as 35 would result if the supports 6 and 7 were not so tapered.

40 It will be obvious that hot steam may be readily introduced through the space between the outer faces of the members 6 and 7, and the edges of the openings in the ends of the main body portion, there being a space left between the seating ridges 14 and 14^a. Or, if the roll has been over-heated in use, 45 cold water may be likewise circulated through the openings for cooling the roll before further use, or during use. Such circulation of heating or cooling fluid is not claimed per se, and since means adaptable for causing such circulation are known, they are not here illustrated.

50 It will be observed that the middle of portion 13 of the shell member is thicker than 55 at the ends, thus giving additional strength.

The interior of the shell member may be left as a rough casting.

By this arrangement a roll made up of seven parts is provided, any one of those parts being replaceable in case it should fail or wear. If the necks break, the spindle may be replaced, without losing any of the other parts; if the forming or face member breaks or wears out it may be replaced without loss of other parts; if it wears or deteriorates in use it may be dressed down, while the remainder of the roll is in service with a different forming member fitted thereon. Shells of different sizes, or with grooves of different contour, etc., may be used with a single 75 spindle.

I claim:

1. A composite roll comprising an axial spindle member threaded at one end, an internally-threaded wedge member adapted to engage the threads on the axial member, a 80 slidable wedge member seated on the other end of the spindle, means to lock the slidable wedge member in position, and a shell member adapted to seat at each end upon the 85 wedge members.

2. A composite roll comprising an axial spindle member, frusto-conical wedge members movably mounted on the axial member, a 90 hollow shell member adapted to seat at each end upon the wedge members, and readily-releasable means to lock the wedge members in adjusted position to support the shell member.

3. A composite roll comprising an axial 100 spindle member threaded at each end, frusto-conical wedge members adapted to move on the axial member, a plurality of seating ribs upon the outer surface of each frusto-conical wedge member, a shell member adapted to seat at each end upon the ribs of the wedge members, and means to move the wedge members and to lock them on the spindle.

4. A composite roll comprising an axial 110 spindle member having necks and wobblers at each end, wedge members adapted to move respectively from each end toward the middle portion of the spindle member, adjustable locking means for said wedge members, and a hollow roll body member adapted to seat at each end upon and to be retained in position by the said wedge members.

5. A composite roll comprising an axial 120 spindle member having the usual necks and wobblers and an intermediate body portion, the ends of the intermediate body portion being threaded, a wedge member adapted to engage one of said threaded portions of the body and to move toward the middle portion 125 thereof upon the threaded portion, a second wedge member adapted to slide on the other end of the spindle, a threaded member adapted to drive the second wedge member inward on the spindle, and a shell member 130

adapted to engage the said wedge members, said shell member comprising a cylindrical portion having flanged inturned portions at the end thereof with tapered openings 5 through the said flanged ends adapted to engage and seat upon the said wedge members.

In testimony whereof, I sign my name.
GEORGE BAEHR.
